HOLDER FOR CASKETS OR THE LIKE

Dude S. Breeden, Pittsburgh, Pa.

Application October 12, 1938, Serial No. 234,627

2 Claims. (Cl. 296—18)

This invention relates in general to a holder and, particularly, to a device of this character adapted to hold a casket on the supporting platform of a hearse.

5 Hearse platforms are usually provided with rollers to facilitate the placing of caskets thereon and their removal therefrom. It has been the practice heretofore to hold the casket in place on the platform by pins removably inserted in 10 one of a row of sockets in the platform at each end and on each side of the casket. Such means for positioning the casket permit considerable movement of the latter particularly when the hearse is travelling over a rough road or up and down hill. It is practically impossible, with such 15 holding devices, to prevent marring or denting of the edges of the casket and there have been cases in which the rear holding pin has been snapped off by the impact of the casket thereon and the casket itself dumped out on the ground.

20 I have invented a novel holding mechanism particularly suited for securing caskets on hearse platforms which prevents any possibility of marring the casket and absolutely precludes movement of the casket during transportation in the 25 hearse. In a preferred form the invention comprises a pair of abutments each having a post insertible into one of the sockets with which hearse platforms are usually provided at each 30 end of the normal position of a casket thereon. One of the abutments is adjustable relative to its post and both abutments are provided with a casket engaging surface composed of yieldable 35 vacuum gripping material. By this means, when the adjustable clamp is tightened, the casket is held positively against movement in any direction. A complete understanding of the invention may be gained from the following detailed 40 description thereof which is to be read in connection with the accompanying drawing illustrating a preferred embodiment. In the drawing:

Fig. 1 is a plan view of a hearse platform illustrating the manner of using the invention to secure a casket thereon;

45 Fig. 2 is a side elevation to enlarged scale partly broken away;

Fig. 3 is an elevation of the forward abutment;

Fig. 4 is a plan view thereof;

Fig. 5 is an elevation of the rear abutment;

50 Fig. 6 is a side view thereof;

Fig. 7 is a view partly in section illustrating a modified construction; and

Fig. 8 is a side elevation taken substantially at right angles to Fig. 7.

55 Referring now in detail to the drawing, a hearse

platform 10 has rollers 11 mounted therein and projecting slightly above the surface thereof to facilitate the placing of a casket 12 thereon. While the disposition of the rollers 11 illustrated is that employed for an end loading hearse, the 5 invention to be described herein may also be applied to a side loading hearse.

The platform 10 is provided with rows of sockets 13, the number of sockets in each row being sufficient to accommodate the usual range of 10 casket sizes. A forward abutment 14 comprises a plate 15 seured to a post 16, said plate being relatively broad as compared with the width of the post. The post 16 has a reduced lower end portion 17 dimensioned to fit tightly in the sockets 13. 15 The reduced end portion of the post is slotted as at 18 to permit contraction thereof when inserted in the socket. A rear abutment 19 includes a post 20 having a reduced lower end portion 21 which fits loosely in the sockets 13. 20 A spring pressed ball 22 mounted in a transverse bore in the reduced lower end portion of the post has frictional engagement with the socket wall.

The abutment 19 also includes a relatively 25 broad plate 23 having guide rods 24 extending rearwardly therefrom through suitable transverse bores 25 in the post 20. A screw 26 is threaded through a tapped transverse bore 27 in the post intermediate the bores 25 and is swiveled as at 30 28 to the plate 23.

Both the plate 15 of the forward abutment and the plate 23 of the rearward abutment have a layer of yieldable vacuum grip material secured thereto as indicated at 29. This material may 35 conveniently be sponge rubber having a plurality of small depressions or pocks formed in its surface. These depressions constitute vacuum gripping surfaces when the abutments are pressed against any surface engaged thereby.

40 The manner of using the holding device will doubtless be understood from the foregoing. The forward abutment 14 is positioned in a socket chosen so as to position the casket substantially centrally of the length of the platform 10. The 45 frictional fit between the reduced lower end portion 17 and the socket prevents turning of the abutment by the vibration to which a hearse is subjected when once it has been properly positioned, so that when a casket is moved into the 50 hearse the gripping surface will face the casket. After the casket has been placed and moved forward along the platform until it engages the forward abutment the rear abutment is positioned with the reduced lower end portion 21 of its 55

post 20 in one of the sockets adjacent the rear end of the platform. The reduced end portion 21 of the post 20 is of slightly smaller diameter than the reduced portion 17 of the post 16 to permit easy insertion in the socket. The screw 26 is then turned until the yieldable plate 29 thereof engages the casket. A few additional turns of the screw cause the layers 29 of the two abutments to engage the casket firmly. The 10 posts may rotate slightly if necessary to cause the gripping surfaces to square up with the ends of the casket and thus bear uniformly thereagainst throughout the width of the abutments. For easy manipulation the screw 26 is provided 15 with a knurled head or knob 30 but any other convenient means of turning the screw may be used instead.

While I have shown the layers 29 and the forward and rear abutments engaging a relatively 20 broad edge portion of the casket 12, I have found that the gripping action of the abutments is substantially the same even where a relatively narrow edge bead is presented thereto.

It will be apparent that the invention is characterized by numerous advantages over the devices of similar nature employed heretofore. It prevents any movement of the casket during transportation and thereby eliminates marring or denting of caskets whether of wood or metal. 30 At the same time, the parts involved are of simple construction and are inconspicuous in appearance. They may also be finished to harmonize with the other metal fittings of the casket and hearse. While I have shown the shanks or 35 reduced end portions of the posts as circular in section, it will be understood that they may also be made of square section for cooperation with hearse platforms having square sockets.

A modification of the invention is illustrated 40 in Figs. 7 and 8. In accordance with this modification the post 20 is slotted as at 31 to receive a half nut 32 slidable therein. The post also has a smooth bore 27' for receiving the screw 26. A cam 33 is pivotally mounted in the slot 31 and 45 has an actuating lever 34 formed thereon whereby when the lever is raised and the half nut lowered, the screw may be advanced freely through the bore 27'. When the layer 29 has engaged the edge of the casket, the lever 34 is pressed down to 50 force the half nut into engagement with the screw whereupon further turning of the screw forces the rear abutment firmly against the casket. By this modification, the operation of locking the

casket in position by advancement of the rear abutment into engagement therewith is materially expedited by reducing the necessary number of turns of the clamping screw.

While I have illustrated and described herein but a preferred form of the invention with a slight modification, it will be understood that changes in the structure described may be made without departing from the spirit of the invention or the scope of the appended claims. Although I have referred herein only to the use of the invention in connection with the handling of caskets, it is also useful for handling other similar articles, e. g., grave vaults, or the like. The cooperating abutments, furthermore, may be disposed on opposite sides of the casket as well as or instead of at opposite ends thereof.

I claim:

1. Holding means for caskets or the like comprising a pair of abutments each mounted on a post insertable into one of a plurality of sockets in a casket support, said abutments having a compressible face and a width several times that of said posts providing an extensive bearing surface for engagement with the casket, one of said abutments having guide rods slidable through its post toward and from a casket disposed between the abutments, and means for advancing and retracting said one of said abutments, the said abutments being rotatable in said sockets, whereby the abutments will square up with the casket when the one abutment is advanced to clamp the casket and hold the same against both longitudinal and lateral movement.

2. Casket clamping means or the like comprising a post having spaced transverse holes therethrough, a clamping plate several times as wide as said post and having a compressible face providing an extensive casket-engaging surface, said plate having guide rods extending rearwardly therefrom and through said holes whereby said plate is slidably supported on said post, and a screw threaded through said post and swiveled to said plate whereby the plate may be advanced and retracted, the said post having its lower end formed to enter a socket in a casket support and adapted for rotation therein, whereby when said means is used with a similar clamping means mounted in a casket support, the plate will square up with the casket when the plate is advanced to clamp the casket, and will hold the same against both longitudinal and lateral movement.

DUKE S. BREEDEN.
